UNITED STATES PATENT OFFICE.

ROBERT J. BARKLEY, OF CHANUTE, KANSAS.

DESIGN FOR AN EGG-CARTON FILLER.

SPECIFICATION forming part of Design No. 29,511, dated October 18, 1898.

Application filed August 23, 1898. Serial No. 689,359. Term of patent 14 years.

To all whom it may concern:

Be it known that I, ROBERT J. BARKLEY, of Chanute, in the county of Neosho and State of Kansas, have invented and produced a new and original Design for an Egg-Carton Filler, of which the following is a full, clear, and exact description.

Reference is to be had to the accompanying drawings, forming a part of this specification, in which similar characters of reference indicate corresponding parts in both the figures.

Figure 1 is a plan view of an egg-carton filler illustrating my design, and Fig. 2 is an end elevation thereof.

The design in its entirety presents the appearance of an oblong rectangular figure composed of a line of squares closed at four sides and a second line of squares closed at three sides only, and, as shown in Fig. 1, two longitudinal strips *a* and *b* appear crossed by strips *c*, ranging transversely. The strip *b* appears at the center of the strips *c*, and the strip *a* appears parallel with the strip *b*

and crossing the adjacent extremities of the strips *c*. The portions of the strips *c* opposite the strip *a* appear individually to jut out from the strip *b* out of proximity to the other elements.

The leading feature of the design is the carton-filler presenting the transverse strips *c*, with the longitudinal strip *b* crossing their middles and the longitudinal strip *a* crossing the strips *c* at one end only and parallel with the strip *b*, the remaining halves of the strips *c* projecting freely and uncrossed by longitudinal strips, and the filler presenting a row of rectangular four-sided figures and a row of rectangular three-sided figures of about equal size.

I claim—

The design for an egg-carton filler herein shown and described.

ROBERT J. BARKLEY.
